UNITED STATES PATENT OFFICE.

SIDNEY B. SHAW, OF SAN FRANCISCO, CALIFORNIA.

CARBURETOR.

Application filed June 3, 1920. Serial No. 386,220.

To all whom it may concern:

Be it known that I, SIDNEY B. SHAW, a citizen of the United States, and a resident of the city and county of San Francisco, State of California, have made a new and useful invention—to wit, Improvements in Carburetors; and I do hereby declare the following to be a full, clear, concise, and exact description of the same.

10 This invention relates particularly to carburetors for internal combustion engines.

Among the objects of the invention are to convert hydrocarbon fuel, such as gasoline, distillate, kerosene, tops and the like 15 into fuel that will readily ignite and burn cleanly in internal combustion engines. A further object is to provide an automatic regulating and controlling mechanism for maintaining constant or an approximately 20 constant ratio between the fuel admitted to the intake and the engine speed; and to cut off flow of fuel to the nozzle of the carburetor when engine is not in operation; to provide an improved means for heating 25 the liquid fuel and to increase its volatility; and to provide an improved carburetor for the utilization of low grade fuels that will be simple in construction, easy to manufacture, and effective for the purpose for which 30 it is designed. Further objects and advantages will appear as this description advances.

In this specification and the annexed drawings, the invention is illustrated in 35 the form considered to be the best but it is to be understood that the invention is not limited to such form because it may be embodied in other forms, and it is also to be understood that in and by the claim 40 following the description, it is desired to cover the invention in whatsoever form it may be embodied.

In the accompanying one sheet of drawings,

45 Figure 1 represents a vertical cross section through a carburetor constructed in accordance with my invention.

Figure 2 is a section taken through Fig. 1 on the line 2—2 thereof.

50 In detail the construction illustrated in the drawings includes a carburetor generally designated by the numeral 1, having an air passage 2 therethrough registering with the neck 3, and joined thereto by the flange 4. The neck 3 is provided with the usual butterfly valve (not shown) for the purpose

of controlling the volume of mixture permitted to pass into the engine cylinders. The body of the air passage is provided with an integral web extension 5 connected to the float chamber 6 having a cork or metallic float member 7 slidably positioned therein on the central shaft 8, having the end thereof bevelled to seat in an opening 9 of the conduit 10 through which hydrocarbon 65 fuel of a combustible nature is supplied from a suitable source or reservoir not shown.

The interior of the air passage 2 is constricted to form the usual Venturi tube. 70 Within the said air passage and adjacent the constricted opening a fuel nozzle 12 formed of copper or other good heat conductor and of any standard design or type, having the central bore 13 therein, and is 75 concentrically mounted on an extended projection 14 passing through the outer walls of the air passage and passing into an extraneous heating means such as a by-pass pipe 15 from either the exhaust manifold 80 or the radiator system. The end of the projection 14 is provided with a tubular terminus 16 presenting a large, superficial area for contact with the heated exhaust gases or the heated cooling medium of the radiator. 85 Thus hot gases and the like, contacting with and passing through the member 16 and that part of the extension 14 exposed, will raise its inherent temperature to substantially the same temperature as the 90 heating medium and by conduction the heat will travel to the unheated portions of the member 14 gradually heating the fuel nozzle 12 within the intake passage 2. The outer exposed surfaces of the fuel nozzle 95 12, and extension 14 within the air passage 2 and where it passes through the air passage walls, are provided with an enclosing heat insulation coating 17, such as mica, for the purpose of retaining the conducted 100 heat within the fuel nozzle and its appendant parts and to prevent escape or loss of heat through contact with adjacent surfaces or by radiation or conduction to air passing through intake passage 2.

105 The interior of the air passage 2 is provided with a diametrically extended web 18 having a centrally enlarged, annular portion 19 drilled to receive the hollow bushing 20, having the central bore 22 therethrough, 110 adapted to be positioned in threaded engagement with the lower end of the fuel nozzle.

12, as at 21, and axially aligning with the central bore 13 provided in the fuel nozzle 12. The hollow pipe plug 23 is detachably mounted within the hollow enlargement 19 adjacent the bushing 20, and is provided with a lateral aperture 24 passing into the central opening 25 in concentric relation with the aligned bores 13 and 22. The web 18 is provided with the conduit 26 aligning 10 with the aperture 24 and extending through the integral arm member 5 into the float chamber 6. Intermediate the float chamber 6 and air passage 2 the casting 5 is provided with a vertical extending projection 15 27 having the needle adjusting valve 28 slidably guided therein. The end 29 of the needle valve 28 is bevelled and is adapted to seat on a valve seat in the conduit 26, thus either stopping or controlling the amount 20 and volume of liquid fuel admitted to the fuel nozzle 12.

The needle valve 28 is automatically operated in the following manner:

An elliptically shaped valve 30 is positioned transversely across the intake passage 3 and fixedly mounted on a shaft 31 having the ends 32 and 33 thereof rotatably mounted in suitable bearings 34 and 35 respectively on opposite sides of casting 3. The 25 end 33 of the said shaft is provided with a cam member 37 rigidly positioned thereon. This cam comprises a substantially annular disc having one-half the periphery thereof struck from the same radius and the remaining half struck from a greater radius to provide an enlargement or projection necessary to give the required cam action. For the 30 purpose of properly holding the valve 30 transversely within the passage 3, the cam 35 37 has a coil tension spring 39 pinned to a part of the said movable cam and its opposite end fixed on the outside of the intake wall at 40. The lever arm 41 securely mounted on the end 42 of the cross shaft 43 40 normally rests in frictional contact with the under surface of the cam member 37. The forked yoke 44, pivotally engaging the needle valve 28 at 45, has the end 46 thereof, fixedly positioned on the cross rod 43 intermediate the extended bearings 34 and 35. The needle valve 28 is operated in the following manner:

The engine in its operation, supposing it to be of multicylinder type, by the movement 55 of the pistons within the cylinders creates a suction on the downward stroke that has an indrawing action upon any carburetted air contained within the passage 3. The sucking action of the pistons is approxi-

mately constant, and without intermittent action, thus substantially maintaining an even supply of fuel through the intake manifold. The aforementioned sucking action tends to move the valve 30 into the vertical position against the tension of spring 39, as indicated by the dotted lines in the Figure 1, thus rotating the cam 37, which forces down on the arm 41, which in turn through the forked yoke member 44 lifts the needle valve 28 from its seat in the fuel conduit 26, permitting the level of the fuel within the nozzle 12 to be substantially on a level with that in the float chamber. Should the engine slow to idling speed and the suction action of the pistons gradually diminish, the position of the gate valve 30 within the passage 3 would likewise change, moving the cam 37 on the lever arm 41 to regulate the needle valve 28 and thus supply a proportionate volume of fuel to the nozzle consistent with the speed of the engine. It will be obvious that by movement of the ordinary butterfly valve (not shown) controlled by the hand or foot throttle of the operator, the amount of the carburetted air admitted to the cylinders can be controlled to regulate the speed of the engine and when worked in conjunction with applicant's automatic fuel controlling and regulating mechanism, the amount of fuel necessary to run the engine at slow 80 speed will be automatically reduced.

Having thus described my invention what I claim and desire to secure by Letters Patent is:

A carburetor, comprising, in combination, 95 a casing having an air passage therethrough; a fuel nozzle in said passage; a reservoir adjacent said casing for supplying fuel to said nozzle; a projection formed integrally with said nozzle and extending outwardly 100 through said casing; insulation surrounding the nozzle and projection and interposed between the nozzle projection and casing; a conduit adjacent said casing adapted to have heated fluid passed therethrough; and means on said projection terminating within said conduit, adapted to be heated by the fluid therein, whereby said projection and nozzle will be heated by conduction, and the heat of conduction transferred to the fuel in 105 the nozzle.

In testimony whereof, I have hereunto set my hand at San Francisco, California, this 29th day of May, 1920.

SIDNEY B. SHAW.

In presence of—
LINCOLN V. JOHNSON.
